CARRIAGE FOR BICYCLES AND THE LIKE

Cynthia Adeline Z. Cone, Rt. 2, Box 363,
Lubbock, Tex. 79415

Filed Sept. 30, 1974, Ser. No. 510,352

Term of patent 14 years

Int. Cl. D12—11

U.S. Cl. D12—114

fig. 3

fig. 4

FIG. 1 is a front perspective view of a carriage for bicycles and the like showing my new design;

FIG. 2 is a rear elevational view thereof with the pivotable lid in a partially raised position;

FIG. 3 is an elevational view thereof with the top half pivoted forwardly; in its open position, the opposite side being a mirror image of the side shown herein; and

FIG. 4 is a top view thereof in its open position, illustrating the interior and the split pivotable shelf disposed therein.

I claim:

The ornamental design for a carriage for bicycles and the like, as shown and described.
